UNITED STATES PATENT OFFICE.

RAY W. BROWN, OF LOS ANGELES, CALIFORNIA, ASSIGNOR TO THE MECHANICAL APPLIANCES CO., OF LOS ANGELES, CALIFORNIA.

PRECISION CONTRAANGLE PIECE.

Application filed April 19, 1926. Serial No. 103,053.

This invention relates to dental hand pieces.

An object of the present invention is to structurally improve dental hand pieces and at the same time secure efficiency in the resultant work with the tool.

Another object is to provide an angle hand piece wherein the driving gear is positioned in such relative angle to the housing and driven gear therein that I am able to wholly eliminate the usual elbow gears set in the bend of an elbow part attached to the housing and, by my invention, I eliminate said part by disposing the driving pinion in a lateral chamber, of the housing, which is at an oblique angle to the axis of the housing and the driven mechanism therein.

Further, an object is to provide a dental hand piece which can be easily cleaned and kept in a highly sanitary condition.

An additional object is to provide a one-piece main bearing box in which the running mechanism has bearing surfaces maintained in true alinement, which is difficult when the bearings are of separate pieces.

And an object is to secure simplicity and reduction of cost by reduction of number of separable parts.

An important object is to provide a structure of this class wherein the reaction of the work is thrust against a part which cannot unthread as a result of the friction imposed.

Other objects and advantages will be made manifest in the following specification of apparatus embodying a form of the invention; it being understood that modifications, variations and adaptations may be resorted to within the spirit and scope of the invention as it is here claimed.

Figure 1 is a side elevation of a full size, angle hand piece. Figure 2 is a plan of the housing and its cap (about double size, as are all of the remaining views). Figure 3 is an axial section of the hand piece. Figure 4 is an axial section of the separate housing. Figure 5 is an axial section of the housing locking nut. Figure 6 is a plan of the top of the housing nut. Figure 7 is a plan of the top of a barrel element. Figure 8 is a side elevation of the barrel. Figure 9 is an axial section of the barrel. Figure 10 is a plan of a collet box and its attached driven gear. Figure 11 is a side elevation

of the box. Figure 12 is an axial section of the box. Figure 13 is an elevation of the collet. Figure 14 is a section of the collet. Figure 15 is an end view of the collet. Figure 16 is a top plan of the collet jam screw. Figure 17 is an axial section of the jam screw. Figure 18 is a side elevation of the jam screw. Figure 19 is a side view of a common dental burr.

The present hand piece is designed to grip a tool having a stem S with or without a D head D, under-cut at neck N.

The hand piece includes a tubular collet 2 with reversible or duplicate conical ends 3 and having longitudinal slots 4 in from each end to enable contraction tightly onto the stem S of any adaptable tool. The collet 2 is designed to slide up in a box 5 having a chamber 6 at the inner end of which is a convergent shoulder 7 to stop the collet and contract it when a jam screw 23 is screwed into threads 8 in the chamber 6.

Fixed firmly on the collet box is a driven gear 10, and at the upper end the collet box has a conical head 9 with a cylindrical bearing rim. The gear 10 also has a cylindrical bearing body 11. The waist of the box 5 is reduced or cut away for clearance, as will appear later. The box 5 and gear 10 are a unit having side and end bearings in a barrel 13.

The barrel has a rounded cap 14 with a narrow flange 15. In the barrel is a conical seat 16 to receive the head 9 of the box 5 and a bore 17 receives the cylinder of the head 9. The open end of the barrel has an enlarged bore 18 to fit the gear body 11 for operation with minimum play. Hence the barrel forms an integral element providing all the side bearings for the running box 5 and forms the inner end thrust bearing 16, which, therefore, cannot work loose under load.

The barrel 13 has external threads 20 and is bodily inserted into a housing 21 which is overlapped by the narrow flange 15 of the cap 14 of the barrel. When the barrel 13 is placed in the housing 21 a clamp nut 22 is screwed up on the threads 20 of the barrel. After the nut 22 is run on (preferably by left-hand threads) a jam nut 23, having a conical seat 24 for the collet 2, is passed through the nut 22 and up into box 5 so as

to jam the collet against the seat 16 and compress the jaws of the collet on the tool stem S when inserted.

If the tool stem has a D head this is received by a D hole 5^a in the top of the box.

Extending at a suitable angle from the housing 21 is a lateral chamber 21^a to receive the co-ordinate end of a driving means usually including a driving pinion 25 10 (Fig. 3).

In common forms of contra-angle hand pieces the drive pinion extends into the housing at a 90° angle. This necessitates an extra outer set of mitered gears in an elbow 15 arrangement to provide the angle in an old and well known manner. A purpose of my present invention is to dispense with the outer set of elbow gears entirely. I do this by disposing the lateral chamber 21^a at an 20 angle of about 20° to the axis of the housing 21, see Figs. 3 and 4. By so doing the drive pinion 25 meshes with the gear 10 at an angle oblique to its axis. The barrel 13 has a side window 13^a for the drive pinion 25 25 and the waist of the box is reduced for clearance.

It will be seen that the box 5 can be pulled axially from the barrel, as soon as the retaining nut 22 has been removed, without disconnecting and removing the drive means 30 from the lateral chamber 21^a, which is necessary in all of the common hand-pieces of which I am aware. This is for the reason that the running box has no collar or 35 band overhanging the associated drive pinion.

What is claimed is:

1. A contra-angle hand piece having a housing with a side chamber for a drive 40 means, a barrel in the housing and having a closed end provided with an inside, end thrust seat, a driven box journalled in the barrel and bearing endwise against said seat, a contractive collet in said box for holding 45 an inserted dental tool, and means attached to said box for contracting the collet.

2. A contra-angle hand piece having a housing with a side chamber for a drive means, a barrel in the housing and having 50 a closed end provided with an inside, end

thrust seat, a driven box journalled in the barrel and bearing endwise against said seat, a contractive collet in said box for holding an inserted tool, means engaging the box for contracting the collet, and means for holding the box in the barrel. 55

3. A contra-angle hand piece having a housing with a side chamber for a drive means, a barrel in the housing and having a closed end provided with an inside, end thrust seat, a driven box journalled in the barrel and bearing endwise against said seat, tool holding means in the box, and means for holding the box in the barrel and for clamping the barrel in the housing. 60

4. In a contra-angle hand piece, a fixed one-piece barrel having an internal closed end thrust seat and cylindrical, coaxial, differential bearing bores, and a running box, for a collet, bearing at one end, against 70 said seat and bearing in said bores.

5. In a contra-angle hand piece, a fixed one-piece, closed end barrel having an internal end thrust seat and cylindrical, differential bearing bores, a running collet box 75 bearing on said seat and bores, and a collet jamming screw in one end of the box.

6. In a dental hand piece, a running collet box having an open bottom end for a collet and provided with an external gear shoulder, a head on the upper end of the box and presenting an internal seat for the collet; the body of the box being unobstructed 80 above the gear so as to slide into a housing to mesh the gear with its driver. 85

7. A contra-angle hand piece having a housing including a lateral chamber, a barrel fitting down in the housing and having a closed head, a drive extending from said chamber into the barrel, a collet box adjustable into the lower end of the barrel and bearing up against the top of the barrel; said box having on its lower end a gear to pass up into mesh with the pinion when the box is inserted at the bottom of the housing, 90 means to support the box in place and securing on the barrel, a collet in the box, and means below the last named means to set the collet. 95
